FREEZING DEVICE

Edmund F. Schweller, Dayton, Ohio, assignor to
 General Motors Corporation, Dayton, Ohio, a
 corporation of Delaware

Application February 16, 1949, Serial No. 76,688

8 Claims. (Cl. 62—108.5)

1

This invention relates to freezing devices for liquids such as ice tray and grid combinations employed in refrigerator cabinets.

In recent years various ice tray and grid structures therefor have appeared on the market wherein the grid structure included a lever mechanism for moving certain of the grid walls relative to certain other grid walls so as to break the bond between ice blocks formed in the ice compartments and walls of the grid and tray for facilitating the removal of ice blocks therefrom. In these structures the lever or an operating bar of the grid wall moving mechanism carried by the grid was designed to lie a substantial distance across the top of the grid and to rest upon the top edge of the walls thereof. Trays with such grid structures therein cannot be stacked or mounted one upon another in a freezing compartment because the lever, lying centrally and longitudinally along the top of the grid, interferes with the mounting of a companion or like tray and grid device thereon.

It is an object of my invention to provide an improved freezing device for disposition in a low temperature compartment.

Another object of my invention is to provide a grid structure which has a lever secured thereto and lying across the top thereof with means whereby the lever, when the grid is positioned in the tray, will not interfere with the mounting and support of another tray thereon.

A further object of my invention is to provide freezing devices each including a tray having a grid therein which may be stacked or mounted one upon another to form a vertical row or tier of such freezing devices within a low temperature compartment.

A still further and more specific object of my invention is to provide a grid for a freezing device with certain walls which extend upwardly beyond certain other walls thereof above the top of a tray associated therewith to form a saddle-like mounting or support for permitting the stacking of one device upon a companion or like device.

Further objects and advantages of the present invention will be apparent from the following description, reference being had to the accompanying drawing, wherein a preferred form of the present invention is clearly shown.

In the drawing:

Fig. 1 shows a refrigerator cabinet provided with a low temperature compartment having freezing devices of the present invention stacked one on top of the other therein;

2

Fig. 2 is a side view of a grid structure construed as herein disclosed and adapted to be positioned in a tray;

Fig. 3 is a top plan view of the freezing device of the present invention showing the grid disclosed in Fig. 2 disposed in a tray;

Fig. 4 is a sectional view taken on the line 4—4 of Fig. 3 showing one transverse wall of the grid having portions thereof extending a substantial distance above the top of another transverse grid wall;

Fig. 5 is a side view of a plurality of freezing devices stacked one on top of the other; and

Fig. 6 is an end view of the stacked freezing devices shown in Fig. 5.

Referring to the drawing, for illustrating my invention, I have shown in Fig. 1 thereof a refrigerating apparatus comprising a household refrigerator cabinet generally represented by the reference character 10 and including an insulated low temperature compartment 11, normally closed by a door 12, and a higher temperature insulated compartment therebelow normally closed by a door 14. The interior of both compartments 20 may be cooled by evaporators of a single refrigerating system or of a double refrigerating system which evaporators may be in the form of conduit convolutions wrapped around and secured to the exterior wall surfaces of the metal liner of each insulated compartment. The refrigerating system with which the evaporators are associated includes a refrigerant translating and circulating unit for withdrawing vaporized refrigerant from one evaporator and for compressing and liquefying the evaporated refrigerant, and recirculating the liquid refrigerant back to the evaporator as is common practice in the art. The interior of compartment 11 is usually maintained, say for example, between 0 and 5 or 10° F. for freezing foods, liquids and for storage of frozen foods. The interior of the compartment closed by door 14 is usually maintained say, for example, between 38, 45 or 50° F. for the storage of other foods such as foods left over from the table. The construction and operation of refrigerators of the type disclosed are conventional and wellknown and since such refrigerators form no part of the present invention a more detailed description thereof is believed unnecessary herein.

My invention is directed primarily to companion or like freezing devices for liquids to be frozen in a low temperature compartment such as compartment 11 of the refrigerator cabinet 10. 55 These freezing devices each include a rectangu-

lar tray and a grid removably disposed in the tray for dividing the interior thereof into a plurality of compartments so as to form ice blocks when water is frozen in the device. In Fig. 2 I show a unitary grid structure 15 comprising a two-part longitudinal upright wall 16 and a plurality of upright walls 17 extending transversely through the plane thereof and being movably interlocked therewith. Suitable provisions are included in the structure of the grid to move certain walls thereof relative to certain other walls so as to break the ice bond between ice blocks frozen in the device and to facilitate removal of the ice blocks therefrom. A leverage mechanism is mounted on and carried by the grid structure for causing the relative movement of its walls. This mechanism comprises a lever 18 pivotally mounted as at 19 to the lowermost part of longitudinal wall 16 and having a link connection 21 with an uppermost part of the two-part wall 16. The detailed construction and operation of such a grid structure is now well-known to the public and for a more specific description thereof reference is made to the Richard M. Storer Patent 2,351,303, dated June 13, 1944, and to the Donald H. Reeves Patent 2,416,119, dated February 18, 1947, since these are the type of freezing devices to which my invention is particularly directed. The unitary grid structure 15 is adapted to be positioned in a tray 24 (see Figs. 3 and 4), and the tray 24 and grid 15 thereby form a freezing device generally represented by the reference character 25 and the walls of which provide a plurality of ice block compartments 26.

It will be noted that the lever 18 of the leverage mechanism on grid 15 lies longitudinally a substantial distance across the top of the grid and rests upon the upper edges of the grid walls. Lever 18 is disposed above the top edge or rim 28 of the side walls of tray 24 when the grid 15 is positioned in the tray and supported upon the flat tray bottom wall 29, as is shown in Fig. 4 and in the Storer patent heretofore referred to. Obviously lever 18 therefore obstructs the otherwise flat top surface of the freezing device afforded by the tray rim 28 and the top edges of walls 16 and 17 of grid 15, and interferes with or prevents the stacking or mounting of one freezing device 25 upon another similar or companion device. In order to permit the stacking or mounting of one device 25 upon another I provide the present grid structure 15 with end transverse walls 31 which have a portion extending upwardly above the tops or uppermost portion of the intermediate transverse walls 17, wall 16 and above the top edge or rim 28 of tray 24 so as to be above the level of the top of lever 18. The lower portion of the two end transverse grid walls 31 are shaped to conform to the shape of the lower portion of the walls 17. Each end transverse wall 31 includes a central portion extending to the top edge of walls 16 and 17 and is provided with raised side portions 33 extending upwardly beyond or above the top edge or uppermost portion of walls 16 and 17 (see Fig. 4). Each of the raised side portions 33 of walls 31 are provided with a flat horizontal top edge 34 located above the level of lever 18 and tapering upwardly or converging into the ears 36. By providing the grid structure 15 with two end transverse walls 31 shaped or of the form as herein shown and described similar or companion freezing devices 25 are each provided with the four flat horizontal surfaces 34 and the upstanding ears 36 in the vicinity of corners of the

rectangular tray 24. The horizontal surfaces 34 and the ears 36 on grid walls 31 cooperate to form a saddle-like support or mounting above the level of lever 18 for the reception of the flat bottom wall 29 of tray part 24 of similar freezing devices 25. This construction permits a tray 24 of one device 25 to be stacked or mounted upon and supported by another device 25 as shown in Figs. 5 and 6, so that the identical or similar and companion devices may be arranged one on top of the other in a vertical tier within the freezing compartment 11 within the refrigerator 10 (see Fig. 1). It will be noted by reference to Figs. 5 and 6 of the drawing that the upper freezing device is supported on the saddle-like, hereinbefore described supports, of the grid in the lower device, in spaced relation to all other portions of the lower device. This prevents the formation of any substantial frost or ice bond between the stacked devices and permits an upper device to be separated from its support on a lower device with a minimum of force or effort. In stacking the freezing devices 25 one on top of the other within a compartment such as compartment 11 the ears 36 on grid walls 31 engage the lower rounded corner portions of a tray 24 to prevent sliding of an upper device 25 horizontally or sidewise relative to a lower device 25. The rear wall of compartment 11 and the inner face of door 12, when this door is closed, prevents sliding movement of an upper device 25 lengthwise relative to another device upon which it is supported or mounted.

From the foregoing it should be apparent that I have made an improvement in the art by providing means in the structure of freezing devices heretofore incapable of being mounted one on top of the other which means renders these devices capable of being stacked to form vertical tiers thereof within freezing compartments. My improvement is accomplished with a minimum of added expense and can be incorporated in freezing devices of present-day design without changing the principle of operation thereof and without materially changing their structure.

While the form of embodiment of the invention as herein disclosed, constitutes a preferred form, it is to be understood that other forms might be adopted, as may come within the scope of the claims.

What is claimed is as follows:

1. A freezing device comprising in combination, a tray and a grid disposed therein, said grid including a longitudinal upright wall and a plurality of spaced apart upright transverse walls interlocked together and dividing the interior of said tray into compartments, and portions of the end transverse walls of said grid extending upwardly beyond the uppermost portion of the transverse walls of said grid intermediate said end transverse walls and above the top of said tray to provide a support at the top of said device above said longitudinal and said intermediate grid walls for receiving the bottom of the tray of a similar companion freezing device.

2. A freezing device comprising in combination, a tray and a grid disposed therein, said grid including a longitudinal upright wall and a plurality of walls extending transversely thereto and being interlocked therewith to divide the interior of said tray into compartments, and portions of the end transverse walls of said grid extending upwardly beyond the uppermost portion of all other walls thereof and above the top of said tray to provide a saddle-like support at the

top of said device above said other grid walls for receiving the bottom of the tray of a similar companion freezing device, and said support preventing sliding movement of the upper device relative to the lower device at least in one horizontal direction.

3. A freezing device comprising in combination, a tray and a grid disposed therein, said grid including a longitudinal upright wall and a plurality of spaced apart walls extending transversely thereto and dividing the interior of said tray into compartments, said walls being interlocked together for movement relative to one another, a leverage mechanism carried by said grid and operable to cause said relative movement of the walls thereof, said leverage mechanism including a lever normally lying a substantial distance across the top of said grid above said tray, and portions of the end transverse walls of said grid extending upwardly beyond the uppermost portion of all other walls thereof, above the top of said tray and above said lever for receiving the bottom of the tray of a similar companion freezing device and supporting the same in spaced relation to said other grid walls and said lever.

4. A freezing device comprising in combination, a tray and a grid disposed therein, said grid including a longitudinal upright wall and a plurality of spaced apart walls extending transversely thereto and dividing the interior of said tray into compartments, said grid walls being interlocked together for movement relative to one another, a leverage mechanism carried by said grid and operable to cause said relative movement of the walls thereof, said leverage mechanism including a lever normally lying a substantial distance across the top of said grid above said tray, portions of the end transverse walls of said grid extending upwardly beyond the uppermost portion of all other walls thereof, above said lever and above the top of said tray to provide a saddle-like support for receiving the bottom of the tray of a similar companion freezing device and supporting the same in spaced relation to said other walls and said lever, and said support preventing sliding movement of the upper device relative to the lower device at least in one horizontal direction.

5. A freezing device comprising in combination, a rectangular tray and a grid disposed therein, said grid including a plurality of walls dividing the interior of said tray into compartments, and certain of said grid walls in the vicinity of corners of said tray having a part thereof extending upwardly beyond the uppermost part of all other portions of said device to provide a support for receiving the bottom of the tray of a similar companion freezing device and supporting the same in spaced relation to said other portions of said first named device.

6. A freezing device comprising in combination, a rectangular tray and a grid disposed therein, said grid including a plurality of walls dividing the interior of said tray into compartments, certain of said grid walls in the vicinity

of corners of said tray having a part thereof extending upwardly above the uppermost portion of all other grid walls and above the top of said tray, said upwardly extending part of said certain grid walls being shaped to provide a saddle-like support for receiving the bottom of the tray of a similar companion freezing device and supporting the same in spaced relation to said other grid walls, and said support preventing sliding movement of the upper device relative to the lower device at least in one horizontal direction.

7. A freezing device comprising in combination, a tray and a grid disposed therein, said grid having a plurality of upright walls dividing the interior of said tray into ice block forming compartments, a portion of at least two of said grid walls extending upwardly beyond the uppermost portion of all other of said plurality of grid walls to provide a mounting at the top of said device above said uppermost portion of said all other grid walls for receiving the bottom of the tray of a similar companion freezing device and supporting the same in vertical spaced relation to said uppermost portion of said all other grid walls, and means on said two of said grid walls projecting above said mounting for engaging a side of the tray of said companion freezing device and preventing sliding movement thereof relative to said first named device in at least one horizontal direction.

8. A freezing device comprising in combination, a tray having a curvature at the junction of its bottom and upright walls, a grid in said tray dividing the interior thereof into ice block forming compartments, said grid having horizontally spaced apart upright wall portions extending upwardly beyond the uppermost part of all other wall portions thereof to provide a mounting at the top of said device above said uppermost part of said all other grid wall portions for receiving the bottom of the tray of a similar companion freezing device and supporting the same in vertical spaced relation to said uppermost part of said all other grid wall portions, means on said horizontally spaced apart upright grid wall portions projecting above said mounting and having an inclined surface substantially corresponding to the curvature of said tray, and said curved inclined surface of said upwardly projecting means nestably engaging the tray of said companion freezing device.
